UNITED STATES PATENT OFFICE.

WALTER A. KRUCK, OF NEW YORK, N. Y.

PNEUMATIC PIANO-PLAYER ACTION.

1,153,554.

Specification of Letters Patent. Patented Sept. 14, 1915.

Application filed July 24, 1914. Serial No. 852,827.

To all whom it may concern:

Be it known that I, WALTER A. KRUCK, a citizen of the United States, residing in the borough of Brooklyn of the city of New York, in the county of Kings, in the State of New York, have invented certain new and useful Improvements in Pneumatic Piano-Player Actions, of which the following is a specification, reference being had to the accompanying drawings, which form a part hereof.

The object of this invention is to improve and simplify the construction of the pneumatic player actions which, under control of the music sheet through the tracker-board, act selectively on those devices which are directly concerned in the actuation of the hammers and dampers and, in an ordinary piano, are actuated by the fingers of the performer through the intermediary of the usual piano keys and abstracts, both the pneumatically operated devices and the finger operated devices usually acting upon the wippens. The ultimate purposes in view are compactness of structure, facility in assembling, reduction in the liability to leakage, and improvement in operation.

The invention is particularly concerned with the construction of the valve-board and its associated parts and with the construction of the mechanical connections of the pneumatics.

The invention will be more fully explained hereinafter with reference to the accompanying drawings in which it is illustrated and in which—

Figure 1 is a view in vertical section of so much of a player piano action as is necessary to enable the invention to be understood, the plane of section being indicated by the broken line 1—1 of Fig. 2. Fig. 2 is a partial and broken view, in front elevation, of the parts shown in Fig. 1. Fig. 3 is a detail view in section on the plane indicated by the broken line 3—3 of Fig. 2. Fig. 4 is a view in elevation of the valve-board and some of its connections, with a portion of the inner wall removed on the plane indicated by the broken line 4—4 of Fig. 3, looking to the right. Figs. 5 and 6 are detail views of the mechanical connections between the lower ends of the abstracts and the player-pneumatics. Figs. 7 and 8 are detail views of the connections between the pivoted guides for the abstracts and the board by which they are supported.

The hammer action, including the hammers *a*, the jacks *b* and the wippens *c*, with the back checks *d* and the damper levers *e*, the finger keys *f* and the extensions *g*, all with their various appurtenances and appliances, may be constructed and arranged in any usual or suitable manner. The wippens are extended slightly, also as usual, for coöperation with the abstracts *h*, which are guided by pivoted guides *i* and are pivotally connected with the movable members of the player-pneumatics *k*.

Each pivoted guiding arm *i* is forked at its outer end, as shown in Fig. 7, and receives, in suitable sleeve washers *i'*, the ends of the pivot pin *i''*. To permit the ready assemblage of the parts each pivot pin is supported by an arm *i³* of a guide plate *i⁴*, which may be suitably secured to the valve-board. The arm *i³* is notched on its under side, near its forward end, to receive the pivot pin *i''*, which is held in place by a clamp *i⁵*, is slotted at its outer end, as at *i⁷*, to straddle a steadyng pin *i⁸*, which projects downwardly from the plate *i⁴*, and is engaged by a headed screw *i⁹* which passes freely through the arm *i³* from above. By backing off the screw *i⁹* slightly the clamp *i⁵* is permitted to drop so as to permit the introduction or removal of the pin *i''*, and by setting up on the screw *i⁹* the clamp is drawn upward to hold the pin securely in position. The depth of the recess *i⁷* is less than the diameter of the pin *i''* so that the pin may be held tightly and without danger of rattling.

As shown in Figs. 5 and 6 the lower end of each abstract *h* is slotted vertically and is provided with a tightening screw *h²*. The two parts of the abstract, at each side of the slot *h¹*, are recessed as at *h³*, and are provided with a cloth lining *h⁴*. The lower or movable member of each player-pneumatic *h* has secured thereto a projecting finger *h⁵* which carries at its forward end, secured in cheek pieces *h⁶*, a pivot pin *h⁷*. Backing off the screw *h²* permits the abstract to be engaged with or disengaged from the pin *h⁷* and setting up on the screw causes the pin to be engaged by the abstract movably but in such manner as to prevent separation.

The mechanical connections of the pneumatic action having been described it remains now to describe the construction of the pneumatic action so far as it involves the player-pneumatics, the valve-board and

the valves, and especially their connections. The particular purposes in view, in this part of the invention are, as already indicated, compactness and simplicity of structure, facility in assembling and in removal of parts for repair, and elimination of unnecessary joints and construction of air connections so as to reduce liability to leakage.

As indicated in Figs. 1-4, the player-pneumatics *k*, the valve-board or common wind-way *m*, and the controlling valves *n*, are combined in a unitary structure which, with the abstracts *h* and guides *i*, can be easily removed and replaced. The player-pneumatics are arranged in several rows, as usual, the player-pneumatics of each row being secured to a common board *l* which is itself secured to the inner wall *m*¹ of the valve-board *m*. The controlling valves *n* are secured, as hereinafter described, to the outer wall *m*² of the valve-board *m*. The two walls *m*¹ and *m*² are spaced apart, at their upper and lower edges and at their ends, by spacing strips *m*³. The interior *m*⁴ of the valve-board constitutes a wind-way or chamber which is common to all of the controlling valves *n* and, through them, to all of the player-pneumatics *k*. This common wind-way or chamber is connected as usual to the wind-trunk and bellows system, these connections being well known and therefore unnecessary to be shown and described herein.

Between the inner and outer, or front and rear walls of the valve-board *m* are placed tubular spacing blocks or sleeves *m*⁵ and *m*⁶. These tubular spacing blocks or sleeves, which form conduits, are usually formed of wood and are glued in place, the front and rear walls and the spacing strips being also held together by glue as well as by screws *m*⁸. The inner or back wall *m*¹ of the valve-board is provided with ports *m*⁷, with which the sleeves *m*⁵ register, and with ports *m*⁸ with which the sleeves *m*⁶ register. The outer or front wall *m*² of the valve-board is provided with ports *m*⁹, with which the sleeves *m*⁵ register, with ports *m*¹⁰, with which the sleeves *m*⁶ register, and with ports *m*¹¹ for communication with the controlling valves *n*.

From the several ports or openings of the usual tracker-board *o* extend the usual connections *n*¹ *n*² *n*³ *n*⁴, to the conduits formed by the sleeves *m*⁵, the conduits *m*⁵¹ for the lower row of connections being conveniently formed through the lower spacing strips *m*³. The supporting-boards *l* for the player-pneumatics are formed with conduits *m*¹² which complete communication between the several player-pneumatics and the corresponding valves *n* through the ports *m*⁸, sleeves *m*⁶ and ports *m*¹⁰, sleeves *m*¹⁴ being secured by glue between the supporting-boards *l* and the inner or back wall *m*¹ of the

valve-board, so as to provide space for the passage of the tubes *n*⁴ which form part of the connections between the tracker *o* and the valves *n*.

The details of construction of the valve *n* form no part of the present invention. As shown clearly in Figs. 1 and 3 each valve preferably comprises in its construction an upper cylindrical part *n*¹, having an apertured boss *n*² to fit tightly against the port *m*¹⁰, with a suitable packing *n*³ interposed, a lower cylindrical part *n*⁴ having an apertured boss *n*⁵ to fit tightly against the port *m*¹¹, with a suitable interposed packing *n*⁶ and having also an L-shaped extension *n*⁷ to fit tightly against the port *m*⁹, with a suitable interposed packing *n*⁸, and an intermediate part *n*⁹. The top of the cylindrical portion *n*¹ is open to permit air at atmospheric pressure to enter the corresponding pneumatic *k* and is provided with a downwardly extending valve-seat *n*^{1x} and the intermediate part *n*⁹ is provided with an upwardly extending valve-seat *n*^{9x}. A piston *n*¹⁰, mounted to move freely in the lower cylindrical part *n*⁴, has a piston rod *n*¹¹ which carries a valve *n*¹² for co-operation with the valve-seats *n*^{1x} and *n*^{9x} respectively.

As will be observed, there are no tubes which extend through the valve-board and must be packed or fit tightly in order to prevent leakage and for which tight joints must be made with the valves, but such conduits as must extend through the valve-board from front to back are formed by the tubular spacing blocks or sleeves *m*⁵ and *m*⁶ and the joints between the valves *n* and the ports *m*⁹ and *m*¹⁰ and *m*¹¹, the first two of which form parts of such conduits, are made by pressing the valves *n* tightly against the front wall *m*² of the valve-board *f*. The ends of the bosses *n*² and *n*⁵ and the end of the extension *n*⁷ of each valve are finished off in a common plane, so that when the valves are held tightly in position, with the interposed packing, tight joints are formed at all points. Each valve is held tightly against the front wall of the valve-board by a saddle or strap *p* which lies across the valve and is held to the front board by screws *p*'.

As will now be seen, the assembling of all parts of the pneumatic action can be accomplished readily, the removal and replacement of the valves when necessary can be effected easily and quickly, there is a minimum of joints which can cause leakage, and there are no joints which are liable to be made to leak by the removal or replacement of any of the valves. Moreover, it will be seen that the communication between the player-pneumatics and the wind-way, through the valves, is direct and free and the danger of choking is reduced to a minimum.

It will be understood that various changes in details of construction and arrangement may be made to suit different conditions of use, without departing from the spirit of the invention, which is not limited to the precise details of construction and arrangement shown and described herein, except as may be pointed out in the following claims.

I claim as my invention:

- 10 1. A valve-board for pneumatic player actions comprising a front wall, a back wall and spacing strips, said walls being provided with ports for communication with the controlling valves and the player-pneumatics, and sleeves interposed between the front and back walls and forming with such ports conduits through the valve-board.
- 15 2. A valve-board for pneumatic player actions comprising a front wall, a back wall and spacing strips, said walls being provided with ports for communication with the tracker-board, the controlling valves and the player-pneumatics, and sleeves interposed between the front and back walls and forming with such ports conduits through the valve-board.
- 20 3. The combination with a tracker-board comprising a front wall, a back wall and spacing strips, said walls being provided with ports, connections from certain said

ports to the tracker-board, connections from certain of other of said ports to the player-pneumatics, controlling valves communicating with still other of said ports, and sleeves interposed between the front and back walls and forming with some of such ports conduits through the tracker-board for establishing communication between the tracker-board, the controlling valves and the player-pneumatics.

4. The combination of a valve-board having ports for communication with the tracker-board and with the player-pneumatics, a player-pneumatic supporting-board having conduits to establish communication between the valve-board and the player-pneumatics, sleeves interposed between the valve-board and the supporting-board and forming parts of said conduits and also serving as spacing blocks to space the supporting-boards from the valve-board, and connections to the tracker-board lying in the space thus formed between the valve-board and the supporting-board.

This specification signed and witnessed this 23rd day of July, A. D. 1914.
